UNITED STATES PATENT OFFICE.

TAGE GEORG NYBORG AND HAROLD CARNEGIE JENKINS, OF WORCESTER, ENGLAND.

JIGGER OR SHAKER CONVEYER.

Application filed October 8, 1927, Serial No. 224,887, and in Great Britain October 20, 1926.

This invention relates to jigger or shaker conveyers operated on or supported by rolling members working on a stationary frame, hereinafter referred to as the underleg.

- 5 One object of the present invention is to provide a conveyer of this kind in which on undulating ground the underleg will adapt itself in a longitudinal direction to the trough.
- 10 A further object of the present invention is to provide an improved construction of underleg.

The drawings filed herewith illustrate the invention, by way of example, and the invention will be described with reference thereto. In the drawings,—

- Fig. 1 is a diagrammatic end view of one form of underleg, showing the trough in position;
- 20 Fig. 2 is a side view;
- Fig. 3 is a plan with the trough removed;
- Fig. 4 is a section through the rolling member; and
- 25 Fig. 5 is a view similar to Fig. 1 of a modified construction.

Referring to Figs. 1 to 4, the underleg comprises an under frame consisting of longitudinal channel members *a*, *a* connected transversely by angle iron members *b*, *b*, and an upper frame consisting of two longitudinal angle iron members *d*, *d* and transverse members *e*, *e*. The upper frame is adapted to support the trough *f*. Two semicircular pivotal supporting members *c*, *c* are disposed below the channel members *a*, *a*.

Between the longitudinal channel members *a* of the under frame and the longitudinal angle iron members *d* of the upper frame are disposed hollow rollers *g*, *g* in each of which is disposed a ball *h*.

The rollers are adapted to take the weight of the upper frame, trough and contents of the trough while the side thrust is taken by the balls.

- 45 In Fig. 5 the trough is riveted by rivets *m* to the transverse members *e*. Bolts *n* are passed through holes in the bottom (or lap) portion of the members *a* and are secured by nuts *o*. These bolts and nuts serve as stops for the rolling members and may be disposed on the top portion of the members *d* or the ends of the members *a* or *d* may be turned inwards to form stops. The rollers *g* and balls *h* are removable for renewal purposes by removing these bolts and nuts.

The pivotal supports *c* allow the underleg

to take up a position parallel to the trough independently of the inclination of the floor in the direction of the trough, one of the supports being packed if necessary to render the frame level transversely. With this arrangement the directional movement of the trough will be independent of the undulations of the floor in the direction of the trough.

What we claim and desire to secure by Letters Patent is:—

1. A shaker conveyer comprising a trough, an underleg supporting the trough, the said underleg comprising an upper member, a lower member, rolling members disposed between the upper and lower members, and pivotal supports secured to the underleg.
2. A shaker conveyer comprising a trough, an underleg supporting the trough, the said underleg comprising an upper member, a lower member, hollow rolling members disposed between the upper and lower members to take the weight of the troughing, and balls disposed between the upper and lower members to take any side thrust.

3. A shaker conveyer comprising a trough, an underleg supporting the trough, the said underleg comprising an upper member, a lower member, hollow rolling members disposed between the upper and lower members to take the weight of the troughing and balls to take any side thrust inserted in the hollow rollers.

4. A shaker conveyer comprising a trough, an underleg supporting the trough, the said underleg comprising an upper member, a lower member, hollow rolling members disposed between the upper and lower members to take the weight of the troughing, balls disposed between the upper and lower members to take any side thrust, and pivotal supports secured to the underleg.

5. A shaker conveyer comprising a trough, an underleg supporting the trough, the said underleg comprising an upper member, a lower member, hollow rolling members disposed between the upper and lower members to take the weight of the troughing, balls to take any side thrust inserted in the hollow rollers, and pivotal supports secured to the underleg.

6. A shaker conveyer comprising a trough, an underleg supporting the trough, the said underleg comprising an upper member, a lower member, hollow rolling members disposed between the upper and lower members

to take the weight of the troughing, balls to take any side thrust inserted in the hollow rollers, and stops for keeping the rolling members in position.

5 7. A shaker conveyer comprising a trough, an underleg fixed to, and adapted to support, the trough, the said underleg comprising an upper member, a lower member, rolling members disposed between the upper and lower members, and pivotal supports secured to the underleg.

15 8. A shaker conveyer comprising a trough, an underleg fixed to, and adapted to support, the trough, the said underleg comprising an upper member, a lower member, hollow rolling members disposed between the upper and lower members to take the weight of the troughing and balls to take any side thrust inserted in the hollow rollers.

20 9. A shaker conveyer comprising a trough, an underleg fixed to, and adapted to support, the trough, the said underleg comprising an upper member, a lower member, hollow rolling members disposed between the upper and lower members to take the weight of the troughing, balls disposed between the upper and lower members to take any side

thrust, and pivotal supports secured to the underleg.

10 10. A shaker conveyer comprising a trough, an underleg fixed to, and adapted to support, the trough, the said underleg comprising an upper member, a lower member, hollow rolling members disposed between the upper and lower members to take the weight of the troughing, balls to take any side thrust inserted in the hollow rollers, and pivotal supports secured to the underleg.

15 11. A shaker conveyer comprising a trough, an underleg fixed to, and adapted to support, the trough, the said underleg comprising an upper member, a lower member, hollow rolling members disposed between the upper and lower members to take the weight of the trough, balls to take any side thrust inserted in the hollow rollers, stops for keeping the rolling members in position and pivotal supports secured to the underleg.

25 In testimony whereof, we affix our signatures.

TAGE GEORG NYBORG.
HAROLD CARNEGIE JENKINS.
